Fig. 2

Fig. 1 is a plan view of a puffed textile fabric, showing my new design; and

Fig. 2 is a sectional view of the fabric along the line 2—2.

The design is embodied in a puffed textile fabric having surface ridges arranged as shown in Fig. 1. Threads interlaced in the fabric, represented by the straight line in Fig. 2, hold the ridges raised.

I claim:

The ornamental design for a puffed textile fabric, as shown and described.
